UNITED STATES PATENT OFFICE

101,471

DESIGN FOR A HAND STAMP

Louis Melind, Chicago, Ill.

Application August 17, 1935, Serial No. 58,175

Term of patent 14 years

To all whom it may concern:

Be it known that I, Louis Melind, a citizen of the United States, residing at Chicago, in the county of Cook and State of Illinois, have invented a new, original, and ornamental Design for a Hand Stamp, of which the following is a specification, reference being had to the accompanying drawing, forming a part thereof.

Figure 1 is a front elevational view of a hand stamp showing my new design; and

Figure 2 is a side elevational view of the stamp of Figure 1.

The particular form of the numerals on the dating bands of the stamp are merely illustrative.

In the design shown the legs of the U-shaped frame taper in width downward corresponding to the downward convergence of the runs of the type strips and, in side view, conceal the internal mechanism of the stamp except for the spaced projecting type characters and the projecting

portions of the discs for adjusting the strips, which characters and discs produce an ornamental effect along the edges of the legs. This, in conjunction with the bridge element connecting the upper ends of the legs and centrally supporting the handle, with its lateral portions inclined downward and outward and seating upon similarly inclined surfaces at the upper corners of the legs, and the platen bar seating in the lower ends of the legs and producing the effect of panels at such locations, imparts to the stamp as a whole a distinctive, novel and attractive appearance. These features constitute the dominant features of the design illustrated.

I claim:

The ornamental design for a hand stamp, as shown and described.

In witness whereof, I hereunto subscribe my name this 13th day of August, 1935.

LOUIS MELIND.
